CLAIM

The ornamental design for a wound pad, as shown and described.

DESCRIPTION

FIG. 1 is a perspective view of a wound pad, showing our new design; and,

FIG. 2 is a top plan view thereof.

The dot-dash broken lines define the bounds of the claimed design and form no part thereof. The claimed design extends to but does not include the boundary line.

1 Claim, 2 Drawing Sheets
